SMOKER

Ira G. Blundell, Sparks, Nev.

Application February 6, 1948, Serial No. 6,654

1 Claim. (Cl. 43—127)

1

This invention relates to a smoke dispensing device, adapted for use to discharge smoke for exterminating gophers or rats, which inhabit ground burrows or pockets.

The principal object of this invention is to efficiently discharge a strong blast of smoke into burrows or pockets formed in the ground, to drive rodents or other ground inhabiting animals out of their lairs or to overcome and asphyxiate them, and to dispel bees and similar insects.

Also, it is an object of this invention to provide means for discharging a constant and strong blast of smoke for fumigating trees, bushes and other shrubbery and for utilization and employment as a frost repelling medium, to protect the fruits of the trees and bushes.

Another object of this invention is to employ means for compressing air and discharging the air within the casing to aid the combustion of fuel placed within the casing and to discharge smoke from without the casing.

A meritorious feature of this invention resides in the provision of a bellows bracketed to a combustion chamber and adapted to discharge air through the combustion chamber to incite and aid combustion of the fuel and to conduct air transversely through the casing, providing a Venturi action to suck the resultant smoke from the fuel out of the combustion chamber and discharge the smoke out of the casing.

Another meritorious feature of this invention resides in the provision of a discharge pipe detachably secured to a connecting pipe communicating with the bellows and the casing and transversely extending through the casing to a point without the casing for discharge of the smoke from the casing to the outer atmosphere.

Another feature of this invention is the provision of a primary source of air for combustion, which includes an angular pipe extending laterally from the bellows and terminating at a point adjacent the combustion chamber.

With these ancillary objects and other meritorious features in view, this invention comprises certain structural features and arrangement of parts as will be more clearly apparent, as the following description proceeds and in view of the accompanying drawings, wherein:

Figure 1 is a side elevational view of a smoking device, constructed according to the principles of this invention;

Figure 2 is a top plan view of the device shown in Figure 1, with the cover removed and,

Figure 3 is an enlarged structural view of the

means utilized to discharge the smoke from the casing and comprises a tubular discharge pipe.

Referring now more particularly to the drawings, wherein an embodiment of this invention is shown, for illustrative purposes, and wherein similar characters of reference refer to similar parts throughout, there is shown a cylindrical casing 10, having its top end open and adapted to a detachably covered by a cover member 12. Centrally disposed and formed in the bottom end, 14, of the casing is an aperture 16, around which is secured, within the casing, a dome-shaped wire screen. This screen 18, forms a fuel bed for the fuel and defines a combustion chamber within the casing.

Secured to the side of the casing, adjacent the open end thereof, is a discharge spout or tube 20, of any suitable size and preferably conical in shape, having its larger end secured to the casing by means of an apertured annular flange 22, formed around the periphery of the enlarged end of the spout. Conventional means are provided to secure the spout to the casing and include telescopic screws or bolts 24, which are inserted through the apertured flange 22 of the spout and through the side of the casing.

Secured to the casing, on the opposite side from the spout 20 is a bellows 26. Suitable means are provided for attaching or securing the bellows to the side of the casing and include a pair of oppositely disposed brackets 28, 30, utilized to secure the connection of the bellows to the casing, and comprise an elongated plate, of a suitable width to space the bellows from the casing, having laterally extending ends 30 and 32. Ends 30 are bent at right angles to the longitudinal plane of the bracket plates 28 and are secured to the cooperating side 34 of the bellows 26 by means of screws 40, which are inserted through apertures in the angular ends 30 and penetrate into and are threaded into the cooperating side 34 of the bellows. Angular terminating sections 32 are arcuate in cross-section to conform to the cylindrical contour of the casing and to be seated flush thereon. Telescopic screws, or other suitable means, 42, are employed to secure the arcuate extensions 32 to the casing 10 and are inserted through apertures formed in the arcuate ends 32 and the casing.

The bellows 26 comprises a pair of oppositely disposed cooperating plate members 34 and 36, which are retained in operative relation, by means of a flexible covering, of suitable material. The material 46 covering the cooperating plates 34 and 36 forming an air-tight chamber there-

between, when the plates are extended, is fixed or secured to the sides of the plates 34 and 36 by suitable means, such as rivets 48.

Disposed within an aperture formed in the lower section of the plate 34 and communicating with the chamber of the bellows and extending laterally from the bellows is a tubular pipe 50, having its terminating section 52 angularly bent from the longitudinal plane of the pipe and converging upwardly to a plane adjacent the aperture 16 formed in the bottom 14 of the casing. Suitable means are provided to maintain the angular portion 52 in spaced relation to the aperture 16 and includes a bracket 54, in which the pipe 50 is seated and which is secured to the bottom of the casing by means of bolts 56, or other suitable means, such as telescopic screws, which are inserted through apertures formed in the laterally extending terminating sections 58 of the bracket 54 and inserted through the bottom of the casing.

Oppositely disposed from the conical spout 20 and in horizontal alignment therewith is a suitable aperture formed in the opposing side wall of the casing. A connecting pipe 60 disposed within the plate 34 of the bellows and communicating with the inner chamber thereof is inserted through the aperture and projects within the casing, terminating at a point in spaced proximity to the side wall thereof. Secured to the connecting pipe by means of a concentric enlarged collar 64 integrally formed on the connecting end thereof is a discharge pipe 62. A tapering discharge nozzle 66 is disposed on the opposite end of the discharge pipe and penetrates a spaced distance within the spout 20. Suitable means are provided to maintain the discharge nozzle in alignment with the discharge opening formed in the spout and comprises a resilient plate 68, having a centrally disposed aperture therein, in which the discharge nozzle is seated and supported. The resilient plate 68 extends upwardly and is supported in an upright or upraised position by means of telescopic screw or bolt 70, which is inserted through a suitable aperture 45 formed in the lower end thereof and secures the plate to the side wall of the casing.

Resilient means are provided to urge or bias the cooperating plates 34 and 36 of the bellows and comprises a compression spring 72, which is secured to the inner surface of the plates by means of upstanding lugs 74 and 76.

In operation, the cover 12, having depending annular flange 13 which is received around the edge of the side walls is removed from the casing by suitable handle means. The discharge pipe 62, which is detachably secured to the connecting pipes 60 by means of the collar 64 is removed from the connecting pipe 60 and from the casing.

Suitable fuel, which will cause a considerable amount of smoke such as rags or other textile and bulk material, is placed in the bottom of the casing on top of the screen 18, which forms a fuel bed.

The discharge tube 62 is then replaced within the casing and inserted on the connecting tube 60 by means of the collar 64, and the discharge nozzle 66 is seated within the aperture formed in the supporting plate 68.

The fuel placed on the fuel bed is then ignited 70 and the cover 12 is replaced on the top of the casing.

The bellows 26 is compressed and air is sucked in the bellows on the release stroke, when the

cooperating plates 34 and 36 are urged apart by the spring 72. When the cooperating plates are moved into engagement with each other, the air is forced through the tube 50 and the discharge end 52, which has a Venturi action forcing more air in and fanning the fire. The air moves upwardly through the fuel bed 18 and aids the consuming of the fuel.

During the same operation, air is forced through the tube 60 and through the discharge tube 62, which also has a Venturi action, and the smoke is sucked out of the casing and forced through the discharge spout 20 formed on the side wall of the casing.

It can thus be seen that there is provided a simple and inexpensive smoking device, that will efficiently facilitate the emission of smoke for any desired purpose, such as the fumigation of trees, bushes or the like, or the smoking out of rodents or gophers from channels or pockets formed in the ground.

It is believed that the foregoing description, when read in conjunction with the accompanying drawings, will be of a sufficient nature to enable those skilled in the art to understand the objectives and structure of the device and accordingly, a more detailed description is not believed necessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention what is claimed as new is:

A fumigator comprising a casing having side walls, an open top end, and a closed bottom end, a detachable cover on the open top end of said casing, the bottom end of the casing having an opening therein, a dome-shaped perforated member secured to the closed bottom end and overlying the opening, a bellows secured to one side of the casing, a draft tube projecting from one end of the bellows having an outer angularly formed terminal section underlying the opening in the closed bottom end of the casing, means for securing the tube to the bottom end of the casing, a tubular member secured to the bellows and projecting into the casing through an opening in the side wall thereof, a conical spout formed on the side wall of the casing opposite said opening, the tubular member terminating in a discharge nozzle positioned within the spout, and a supporting bracket secured to the interior of the casing and supporting the nozzle end of the tubular member.

IRVING BLUNDELL.
